PRESSURE OPERATED VALVE

Arvid Lundquist, New York, N. Y., assignor to
 R. Hoe & Co., Inc., New York, N. Y., a corporation of New York

Application February 24, 1932. Serial No. 594,889

9 Claims. (Cl. 9—44)

This invention in general relates to liquid measuring devices, and more particularly to a fluid-operated device for ejecting or depositing predetermined amounts of adhesive when desired upon webs or web rolls mounted on or feeding to printing machines.

The object of the device is to provide an improved, simplified device of the character indicated that will provide means for depositing an invariable or predetermined amount of adhesive on a desired portion of a web roll or the web thereof.

Another object is to provide a device of the kind indicated of comparatively simple and inexpensive design and construction and one particularly adapted to be conveniently secured to printing mechanism for depositing or ejecting adhesive in predetermined quantities on a web roll or web which may be feeding to said printing mechanism.

It is also an object of the invention to provide a liquid measuring device of generally improved construction, whereby the device will be simple, durable and inexpensive in construction, as well as convenient, practical, serviceable and efficient in its use.

The invention will be best understood in connection with the accompanying drawing, in which:

Figure 1 is a longitudinal, sectional view of an embodiment of my invention;

Figure 2 is a transverse sectional view taken on line 2—2 of Figure 1;

Figure 3 is a transverse sectional view taken on line 3—3 of Figure 1, looking in the direction of the arrows;

Figure 4 is a transverse sectional view taken on line 4—4 of Figure 1, looking in the direction of the arrows;

Figure 5 is a plan view of the valve stem or spindle removed from the assembly; and

Figure 6 is a bottom plan view of the device.

For the purpose of illustrating my invention I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

With more particular reference to the drawing, 11 designates a valve casing or box composed of an upper portion 12 having a fluid pressure chamber

13, and of a lower portion 14 suitably secured, as hereinafter described to the upper portion 12 and having an adhesive-containing chamber 15 provided therein. The upper portion 12 of the valve casing 11 is provided with a top member 16, having a reduced threaded stem 17 formed integrally therewith, the top member 16 being fastened to the upper portion 12 by screw bolts 18 which also serve to fasten the lower portion 14 to the said upper portion. A passage or hole 19 formed in a partition or bottom 20 of the upper portion of the casing provides communication between the fluid pressure chamber and adhesive-containing chamber above mentioned, the partition having a shoulder 20'. The passage 19, which is formed as 70 a valve seat, is normally closed by an angular valve head 21 received in the said passage of the partition 20. The valve head 21 is secured to or formed integrally with a valve stem or spindle 22 which extends into both chambers 13 and 15 and on 75 which is arranged a spring 23 seated at one end on the shoulder 20' of the partition 20 and engaged at the other end with an adjustable spring guide and tensioning member 24 threadedly engaged on the stem of a screw 25, fastened to the 80 upper part of the valve stem 22 and having a nut 26 serving as a stop on the extremity thereof. The stem of the screw 25 is freely slideable in a hole 27 provided in a valve stem guide or plate, which is formed with vents or openings 29 to 85 admit fluid under pressure into the chamber 13.

The adhesive-containing or lower chamber 15 has an inlet or opening 31 in which the stem of a pipe 32 leading to the adhesive supply (not shown) is threadedly engaged. A plate 33 having a hole 34 registering with the inlet opening 31 is secured to the wall of the chamber 15 by a screw 35 and has fastened thereto by another screw 30 formed of any suitable material, such as rubber, leather, or the like, a flap valve 37 95 functioning to open and close the opening 31 as adhesive is admitted into the chamber 15 through the said opening or expelled from the chamber 15 through a conical-shaped opening or passage 38 in a plate or disk 39 secured to the 100 bottom of the lower portion 14 of the casing 11 by screws 40 and preferably provided with small dowel pins 42 for conveniently aligning the said plate 39 on the bottom of the lower member 14. The opening 38 in the plate 39 is normally closed 105 by an angular valve head 41 seating therein and secured by a screw 43, fastened to the bottom of valve stem 22. Spanner holes 44 in the angular head 41 provide means for turning or adjusting same, when desired.

The function and general manner of operation of the device has been in large measure indicated from the foregoing description, it being understood, that the present valve assembly is attached by the threaded stem 17 to any convenient outlet of a source of compressed air or fluid controlled in any suitable manner, either automatic or manual, the compressed fluid being admitted when desired into the interior of chamber 13 through the openings 29, in the valve stem guide or plate 28. Assuming the chamber 15 is filled with adhesive and that compressed air or fluid has been admitted into the chamber 13, the spring-loaded plunger which includes the valve stem 22 and valve heads 21 and 41 will descend, and thus move the valve heads 21 and 41 from their respective seats in the passages 19 and 38, thereby permitting the adhesive in chamber 15 to be ejected through the now open passage 38, it being observed that the flap valve 37 has functioned to close the hole 34 during the ejecting period. When the contents of chamber 15 have been ejected, glue or other suitable adhesive will again be permitted to flow by gravity, or under pressure, through pipe 32, hole 34, against the flexible flap 37 which will now be deflected to admit the adhesive until the chamber 15 is filled anew. The chamber 15 it is to be understood, while not permitting the escape of the adhesive therefrom, until the valve head 41 descends, nevertheless allows the air therein to seep out as the adhesive is forced in through pipe 32, the valve head 41 being arranged to fit its seat loosely so as to permit the escape of air but not of adhesive, and I have not found it necessary in practice to provide means for the escape of air other than described.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim is:

1. A device of the kind described, comprising a casing composed of two parts, one of said parts having a chamber formed therein and adapted to admit fluid under pressure, a partition having a shoulder thereon arranged in said chamber, a spring seated on said shoulder, another of said parts having a chamber formed therein, said chamber being adapted to contain adhesive, an adhesive-admitting inlet arranged in said last-mentioned chamber, a flap normally closing said inlet but admitting adhesive into the adhesive-containing chamber when desired, and valve-operated means for normally closing the adhesive-containing chamber, but yielding to fluid admitted through the first-mentioned chamber under pressure, whereby a predetermined amount of adhesive may be ejected from the adhesive-containing chamber.

2. An adhesive-depositing device of the kind described, comprising in combination, a casing, a pair of chambers formed in said casing, a partition arranged between said chambers, an opening formed in said partition, a yieldingly mounted valve member seating in and adapted to open and close said opening, an inlet for admitting adhesive in one of said chambers, a valve normally closing said inlet, and an outlet in said last-mentioned chamber for permitting the escape of adhesive therefrom, said outlet being

opened and closed simultaneously with the opening and closing of said opening by the yieldingly mounted valve member.

3. In a device for ejecting a measured quantity of liquid, a chamber having a liquid inlet valve, an outlet valve and an air inlet valve; said air inlet valve being arranged to open upon application of air under pressure exteriorly and to simultaneously open the outlet valve.

4. In a device of the character described, the combination of a casing adapted to be operably connected to a source of fluid under pressure, a plurality of chambers provided in the casing, a valve stem movably mounted in said chambers and having a plurality of valve heads, a plurality of passages formed in said casing and communicating with said chambers, said valve heads coacting with said passages to open and close same, spring means engaged with said stem and casing, an inlet formed in the casing, said inlet communicating with one of said chambers and a source of adhesive, and a flap valve normally closing said inlet but adapted to open same to admit adhesive when said last-mentioned chamber is unfilled, whereby when said valve stem is moved by fluid under pressure acting on one of the valve heads, all of said valve heads will be actuated and adhesive contained in one of the chambers will be ejected therefrom.

5. In a device of the character described, the combination of a fluid pressure chamber and a communicating adhesive containing chamber, valve means normally closing one of said chambers but operable by fluid under pressure when admitted to another of said chambers, inlet and outlet openings formed in said adhesive containing chamber, a flap valve yieldable to adhesive forced into said first-mentioned chamber through said inlet opening, but closing said inlet opening when adhesive contained in said chamber is forced out by said fluid under pressure, said outlet opening permitting the escape of air from the adhesive containing chamber when adhesive is forced therein, and allowing adhesive to escape when the valve means are actuated by fluid pressure.

6. In a device of the character described, the combination of a fluid pressure chamber and a chamber adapted to contain adhesive, valve members arranged in the chambers, resilient means engaged with the said valve means for normally retaining them in position for closing said chambers but permitting them to yield to fluid under pressure admitted to the fluid pressure chamber, and inlet and outlet means connected to the last-mentioned chamber, said inlet means being operable for admitting adhesive to the last-mentioned chamber, but preventing same from escaping through said inlet means, said outlet means permitting the ejection of adhesive from the chamber adapted to contain adhesive.

7. In a device of the kind described, a casing, a chamber formed in said casing, said chamber being adapted to contain adhesive, a valve stem arranged in said casing, valve members secured on the stem, openings in the said chamber, said openings being adapted to be opened and closed by said valve members, a third opening formed in the chamber, and serving to admit adhesive, a check valve normally closing said last-mentioned opening, one of said first-mentioned valve members serving to admit fluid under pressure to enter the chamber to eject adhesive contained therein.

8. An adhesive applying device of the kind described, comprising a casing, a pair of chambers

formed in said casing, one of said chambers having an inlet to receive adhesive and an outlet to eject adhesive, a pair of valves arranged in said casing, a communicating passage between said chambers, one of said valves normally closing said communicating passage, a check valve normally closing said inlet but admitting adhesive therein, the other of said pair of valves serving to normally close said outlet, and means for admitting fluid under pressure into another of said

pair of chambers for operating both of said valve members, whereby adhesive will be ejected from the device.

9. In a device of the kind described, a chamber having an air inlet valve, an exhaust valve arranged to be operated by movement of the air valve, a spring arranged to normally close the air valve, an inlet for liquid adhesive, and a check valve for the said inlet.
